CLAIM

The ornamental design for a camera filter frame, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top and right side perspective view of a camera filter frame.

FIG. 2 is a bottom view thereof.

FIG. 3 is a front view thereof.

FIG. 4 is a back view thereof; and,

FIG. 5 is a cross sectional view thereof, taken along line 5-5 of FIG. 3.

The broken lines depict portions of the camera filter frame in which the design is embodied that form no part of the claimed design.
